M. J. BRANDT

BUST SUPPORT

Filed April 6, 1922

UNITED STATES PATENT OFFICE.

MATHILDE JOHANNA BRANDT, OF NEW YORK, N. Y.

BUST SUPPORT.

Application filed April 6, 1922. Serial No. 550,033.

This invention relates to bust supports such as are frequently worn by women, and it is an object of the invention to provide a bust support which will act as a form which has been designed or moulded to shape.

It is a further object of the invention to provide a bust support which will support the breasts without exerting pressure upon them from above, but which will, on the contrary, support them by a yielding upward pressure in a manner such as not only to prevent the breast muscles from being stretched, but to promote the development or hardening of such muscles and make them capable of supporting the weight of the breasts without sagging.

To this end an important feature of the invention resides in the provision of a bust support with breast receiving pockets formed of woven material cut on a bias and suitably arranged to provide an efficient support or form and yet give desirable yielding ability at the front and along the shoulder portions of the support.

In accordance with a further feature of the invention, each side of the body portion of the improved bust support consists of a single piece of goods from its front edge adjacent to which it is attached to one of the breast receiving pockets to a centrally disposed back seam, and the body portion is also cut on a bias within certain areas to cause the support to yieldably adapt itself to the movements of the bust in breathing and to the play of the back muscles and of the large muscles back of the shoulders which move the arms.

Other objects and features of the invention will appear as the description proceeds and will be pointed out in the appended claims.

In the drawing:

Fig. 1 is a view in front perspective showing a bust support constructed in accordance with the invention as it appears upon the wearer;

Fig. 2 is a view in perspective showing the support from the rear;

Fig. 3 shows a form of the support adapted to be worn without corsets;

Fig. 4 shows a form of the bust support designed to be worn with corsets, and

Figs. 5 and 6 are detail views showing the means for holding the ends of the shoulder tapes and for adjusting the length of the sections of the tapes.

Similar characters of reference indicate corresponding parts throughout the various views.

The illustrated bust support comprises a body portion of woven material of a kind commonly used in the making of women's underclothing, such, for example, as cambric, and consists of side portions 10 and 12. As shown, the side portions 10 and 12 and the parts associated with them are substantially identical in construction, and such portions are connected at their rear edges by a back seam 14.

Adjacent to their front edges, the side portions 10 and 12 of the bust support are provided with breast receiving pockets 16 which are cut on a bias both at their upper edges and at their lower edges where they are connected to the body portion of the support by bias seams 20, which are preferably abruptly curved at their central portion relative to their end portions. Each of the breast receiving pockets 16 is preferably supported at its upper edges at spaced points 22 and 24 located on opposite sides of and at substantially equal distances from the vertical center line of the pocket. The breast receiving pockets 16 are not only cut on a bias, but they are preferably also so cut that when the bust support is in place on the wearer, vertical planes through the pockets 16 are diagonal to the threads of the pockets, or, in other words, substantially bisect the angles formed by intersecting threads of the pockets.

A piece of ordinary woven material, such, for example, as cambric, will yield but slightly to a pull exerted in line with the threads of the cloth whether the pull is exerted in the direction of the weft or of the warp. Such fabric will, however, yield readily, and to a considerable extent in response to a force exerted diagonally of the threads. In the drawing the direction of the threads is indicated by cross marks, and the direction of

the forces to which the support is subjected in wear is indicated by broken lines. In Figs. 1 and 3 of the drawing, the direction of the force arising from the weight of the breasts is indicated by the broken lines A—B, it being understood that, as shown in Fig. 3, the front ends of the bust support are located considerably below the positions which they occupy when the garment is in place 10 on the wearer with relation to the back portion of the support, and that when the support is being worn, the lines A—B are substantially vertical as well as diagonal to the threads of the fabric thus enabling the breast receiving pockets to yield to the maximum 15 degree to the weight of the breasts.

In the use of the bust support the breast receiving pockets are supported at the points 22 and 24 by means which will be herein- 20 after described, and act yieldingly and upwardly upon the breasts, so as to cause them to be reduced in size not by any considerable degree of pressure, but by being merged to a considerable degree and in a natural manner with the flesh of the bust above the breasts. In wearing the improved bust support a condition of action and reaction is established between the flesh of the breast, on the one hand, and the fabric of the breast 30 receiving pockets on the other, so that in the movements of the wearer the breast receiving pockets are sometimes caused to yield somewhat to movements of the breasts, assuming that the breasts are otherwise left free to move, and the breasts at other times move upwardly to some extent in response to the yielding upward pressure imposed upon them by the pockets, the breasts being at all 35 times, however, supported by the breast receiving pockets in such a manner as absolutely to prevent stretching of the breast muscles or sagging of the breasts. In this manner the weight of the breasts is borne largely by the breast receiving pockets 16, 40 and the condition of action and reaction above explained between the breasts and the pockets 16, while the breast muscles are largely relieved from the weight of the breasts, causes such muscles to be developed 45 or hardened, so as to render them capable of supporting the breasts without sagging.

In order to enhance the supporting effect of the breast receiving pockets 16 the body portion of the bust support below the middles 55 of the bias seams 20 is preferably cut straight, as indicated at 26, and is reinforced by darts or gussets 28 formed by tucking or folding the fabric of the support and stitching along the edges of the folds. The 60 body portion is also preferably formed with darts 30 extending inwardly from its front edges. The darts 28 and 30 not only provide reinforcements for the body portion of the bust support but also modify somewhat the 65 direction of the threads so that panel 26 is

cut straight, whereas panels 26' and 26'' adjacent thereto and panel 26''' are inclined, thus enabling the bust support to better adapt itself to the movements of the body in breathing and to the play of the muscles. 70

Preferably, and as shown, the sides of the body portion of the bust support are cut substantially straight from their front edges to approximately the points indicated at 32 in Figs. 3 and 4. In the form of the invention 75 shown in Fig. 3, the body portion of the support is cut on a bias between the points 32 and the back seam 14. The bust support at its upper edge is cut along a curved line 36 inclined upwardly and running at a slight bias to the fabric to a point 38, and is then cut along a downwardly inclined curved line 40 at a larger bias from the point 38 to the back seam. In this manner the back 80 of the body portion of the support is provided with upwardly extending angular areas 42. The front seams 30' are also on the bias and yield.

By reason of the manner in which the sides 90 10 and 12 of the body portion of the bust support are cut, the threads of the support are arranged on a bias along the line E—F indicating the direction of the force exerted by the movements of the body in breathing, thereby enabling the support to stretch to an extent such as to cause it to yield readily to breathing and form no impediment thereto. As appears from Fig. 2, the lines E—F 95 in the angular areas 42 at the back of the bust support substantially bisect the angles formed by its intersecting threads, and such areas also yield readily in a vertical direction along the line O—P which is also diagonal with reference to the threads.

The bust support is provided on its outer 100 surface along its upper, lower and front edges with tapes, and at the tips or apices of the angular portions 42 with an extra ply of fabric overlying the ends of the tapes. 110 For purposes of ornamentation, the improved support is also preferably provided along its upper edge with a fringe of lace 43. As shown, the tape or braid along one of the front edges of the body portion of the support is provided with eyes 44 arranged for 115 engagement with hooks 45 attached to its opposite front edge for securing the garment in place on the wearer.

The upper edges 18 of the breast receiving 120 pockets 16 are preferably supported by members arranged to pass over the shoulders of the wearer and connected with the angular areas 42 at the back, thus enabling the breast receiving pockets to adapt themselves yieldably to movement of the breasts not only because of their own yielding character by reason of being cut upon a bias, but also by reason of the ability of the angular portions 42 to yield readily along the lines O—P 125 because of being also cut on a bias. 130

The supporting means for the bust support preferably comprises fastenings 46 provided with studs 47 adapted to be received in openings in the upper edges of the breast 5 receiving pockets 16. The fastenings 46 are also formed with slots which receive the ends of relatively narrow shoulder tapes 48. Each of the tapes 48 is turned edgewise at its middle portion and folded over flat to 10 provide a reinforcement 50, and the ends of the sections or lengths of the supporting tape 48 terminate in enlargements 54, and pass first forwardly through the slot 56 of the member 52 and then rearwardly through 15 the slot 58. From thence the sections of the tape 48 extend through the slots in the fastenings 46, and then again through the slots 56 and 58 of the plate 52 over the forward surfaces of their end portions, as clearly 20 shown in Fig. 5. As shown in Fig. 6, the enlargements 54 of the sections of the tape 48 are arranged in line with each other at the opposite ends of the plate 52, the arrangement being such that the plate 52 constitutes means common to both sections of 25 the tape 48 for holding their ends and adjusting the length of the sections.

If desired, the supporting members may also be themselves made yieldable by the 30 provision of elastic tapes 60 between the rear ends 50 of the tapes 48 and the angular areas 42. The tape 60 is provided at its ends with buttons 62 and 64 for engagement respectively with the end 50 of the 35 tape 48 and with a button-hole 66 in the angular area 42. The elastic tape 60 is more or less rough and might feel disagreeable if allowed to contact with the skin of the wearer. Accordingly, therefore, the 40 tape 60 is preferably encased in an extensible envelope 68 of soft fabric.

When the bust support is in position on the wearer, the angular areas 42 overlie the bases of the relatively large muscles at 45 the back of the shoulders which move the arms, it being apparent from the foregoing, however, that by reason of the areas 42 being cut on a bias, as hereinbefore explained, the fabric of the body portion of 50 the support will yield readily along the line O—P, thus causing the support to adapt itself readily to the play of such muscles. It will also be apparent from Fig. 3 that the 55 body portion of the bust support will also yield readily along the vertical lines m—n to adapt itself to the play of the back muscles.

The bust support is preferably reinforced along the back seam 14 by a tape 70, and 60 in the form best adapted for being worn without corsets, it is provided with an elastic loop 72 depending below the tape 70 for attachment to another article of clothing.

In the form of the support adapted to be 65 worn with corsets, as shown in Fig. 4, the

body portion between the points 32 and the back seam 14 is formed with triangular portions 80 which, if desired, may be reinforced by darts 82. At their tip ends the triangular portions 80 are provided with 70 suitable fastenings 84 to which is connected an elastic band 86 adapted to be drawn around the front of the corset.

It will be seen that my improved bust support is adapted to act as a forming member 75 and cause the body to be adapted to that form. At the same time yieldable features are provided as hereinbefore described so that the body is comfortably housed, and no strain exerted on that part of the 80 body. I do not wish to be limited to the devices of the embodiments shown.

Having fully described the invention, what is claimed is:

I claim—

1. A bust support comprising a body portion composed of a pair of like one-piece side portions secured together at their rear edges by a back seam, separable fastening means carried on the front edges of said side portions, a breast receiving pocket carried on each of said side portions and comprising fabric cut on a bias at both its upper and lower edges in such direction as to dispose the threads of the pocket diagonally 95 to the normal vertical planes through the pocket to brace the pocket against vertical sagging and admit lateral yielding to a limited extent and connected at its lower edge to the upper edge of the side portion by a bias seam, each of said side portions beneath the middle of said bias seam being 100 cut straight to dispose the threads crosswise beneath the breast pocket and provided beneath its breast pocket with folded gussets 105 in the lower and front edges of the side portion extending into proximity to the breast pocket for supporting the latter, said side portions being cut at their lower edges 110 downwardly on a bias and converging downwardly into said back seam, and shoulder engaging supporting means connected each at one end to the back of the body portion and at the other end to the adjacent breast pocket at points spaced at opposite sides of the medial vertical plane of the same.

2. A bust support comprising, a body portion consisting of two pieces of fabric material each having a front portion having its lower edge cut with the weave of the material, and downwardly thereacross on a bias to form the back portion which will 120 yieldingly adapt the body portion of the support to the movements of the bust of the wearer and having its upper edge cut along curved lines, said pieces being joined together by a seam in the back and having co-operating fastening means along their front 125 ends, breast receiving pockets connected to 130

the upper edge of the front portion of each
of said body pieces, each comprising a sep-
arate piece of woven material with the
weave thereof arranged on a bias with re-
spect to the front body portion and the
direction of force arising from the weight
of the breasts, and a supporting strap con-
nected with each breast pocket and the back
portion of the body piece to which the
pocket is connected. 10

In testimony that I claim the foregoing
as my invention, I have signed my name
hereunder.

MATHILDE JOHANNA BRANDT.
